DOUBLE DOWEL BAR EXPANSION JOINT

Filed Sept. 24, 1937

UNITED STATES PATENT OFFICE

2,121,303

DOUBLE DOWEL BAR EXPANSION JOINT

Robert R. Robertson, Chicago, Ill., assignor to
The Translode Joint Company, Chicago
Heights, Ill., a corporation of Illinois

Application September 24, 1937, Serial No. 165,439

7 Claims. (Cl. 94—18)

The present invention pertains to road joints and more particularly to an improved type of road expansion joint adapted to be embedded between adjacent concrete road slabs, said joint including in combination a precast plastic filler board adapted to be supported upon a road sub-grade and having openings provided therein at spaced intervals for the reception of adjustable load transmission units, each of which consists of overlapping dowel bars, the outer ends of which are formed to be anchored in the adjacent road slabs while the inner ends of the dowel bars project in opposite directions through an opening of the filler board and into pockets or housings forming part of flanged supporting plates engaged on opposite sides of the filler board with the flanged portions of the plates resting upon the road sub-grade and staked thereto.

It is an object of this invention to provide a road expansion joint comprising a preformed plastic filler board having openings provided at spaced intervals throughout the length thereof for the reception of slidably overlapping double dowel bars, carried in supports on opposite sides of the filler board and anchored in the adjacent road slabs for the transmission of loads from one road slab through the joint to an adjacent road slab.

It is also an object of this invention to provide a road expansion joint including a preformed filler board having openings therein to permit a plurality of sets of slidably overlapping double dowel bars to project therethrough, with the outer ends of each set of the dowel bars anchored in adjacent road slabs and having the inner ends engaged in protecting pockets forming part of supports for the double dowel bars and disposed on opposite sides of the filler board.

Another object of the invention is the provision of a road expansion joint in which an apertured filler board has a plurality of sets of overlapping dowel bars projecting therethrough with the outer ends of the dowel bars anchored in adjacent road slabs while the inner ends of the dowel bars are slidably engaged in pockets provided in the road slabs opposite from the slab in which the outer ends of said dowel bars are anchored.

It is an important object of this invention to provide an improved concrete road expansion joint mechanism including a preformed plastic filler board having openings provided at spaced intervals therein for the reception of load transmission units, each of which consists of a pair of spaced angle supports positioned on opposite sides of the filler board and provided with pro-

tecting housings affording recesses for the reception of the inner ends of dowel bars which project in slidably overlapping engagement through a filler board opening and have the outer ends thereof formed to provide anchors for anchoring the outer ends of the dowel bars in adjacent road slabs.

Other and further important objects of this invention will be apparent from the disclosures in the specification and the accompanying drawing.

The invention, in a preferred form, is illustrated in the drawing and hereinafter more fully described.

On the drawing:

Figure 1 is a fragmentary side elevation of an expansion joint forming mechanism embodying the principles of this invention and disclosing the apertured filler board with spaced load transmitting units engaged therein and showing one of the openings unfilled.

Figure 2 is an enlarged sectional view taken on line II—II of Figure 1 showing the expansion joint forming mechanism embedded in the concrete road slabs and supported on the road sub-grade, and furthermore illustrating one-half of one of the units in elevation, while the opposite half is in section.

Figure 3 is an enlarged vertical detail section taken on line III—III of Figure 2.

Figure 4 is a fragmentary side elevation of a portion of a modified form of road expansion joint load transmission unit wherein the dowel bar supports are provided with modified forms of pockets or housings for the reception of portions of the overlapping dowel bars.

Figure 5 is a fragmentary transverse detail section taken on line V—V of Figure 4.

As shown on the drawing:

The expansion joint, as illustrated in Figures 1 to 3 inclusive is formed by means of joint forming mechanisms adapted to be supported on a road sub-grade 1 for embedding between concrete road slabs 2 and 3.

The improved expansion joint forming mechanism comprises a preformed or precast plastic filler board 4 constructed out of asphalt, sponge rubber, cork, or any other suitable compressible material, such for example as a compressible material known to the trade as "Flexcel". The filler board or core member 4 is provided with a plurality of spaced openings 5 for the reception of load transmitting means forming a part of a load transmission unit, one of which is associated with each of the filler board openings 5.

Each of the load transmission units comprises a pair of oppositely positioned metal plates 6 adapted to be positioned against opposite sides of the filler board 4 adjacent one of the openings 5. Each of the metal plates 6 has integrally formed on the lower margin thereof an outwardly projecting base flange 7 which seats upon the top surface of the sub-grade 1, as clearly illustrated in Figure 2. Each of the metal plates 6 has an opening formed therein by striking outwardly a flange 8. A socket or housing is secured to the outer side of each of the plates 6 in register with the opening in the plate 6 and with one of the openings 5 in the filler board 4. The socket or housing comprises a top plate 9, the side margins of which are deflected to provide side walls 10. One end of the top wall 9 is bent outwardly to provide a mounting flange 11 which is spot welded or otherwise rigidly secured to the outer surface 20 of a plate 6. The outer end of the top plate 9 is deflected to provide an end wall 12 and a projecting flange 13.

Each of the sockets or housings which are attached to the plate 6 has an open portion opposite the plate 9 which is closed by means of a dowel bar 14 to which the socket or housing flange 13 is spot welded or otherwise rigidly secured. The dowel bar has slidable contact with the plate flange 8 which acts as a guide for the 30 slidable movement of the dowel bar. The outer end of each dowel bar 14 is longitudinally split with the split portions deflected upwardly and downwardly to form anchoring fingers or blades 15. The end portion of each of the dowel bars 35 opposite the anchoring blades 15 projects through the opening in the plate 6 and through an opening 5 of the filler board 4 and then through the opening in the opposite plate 6 and into a chamber 16 in the opposite socket or housing. This 40 arrangement, as clearly illustrated in Figure 2, positions the inner end portions of the two dowel bars 14 in slidable overlapping engagement with respect to one another, so that the two dowel bars project through an opening 5 of the filler board 4 in opposite directions permitting the ends 45 of the dowel bars to have slidable engagement in the sockets or casings provided on the joint plates 6 on opposite sides of the filler board.

The improved expansion joint forming mechanism, as hereinbefore described, comprises the apertured filler board 4 which has associated therewith a plurality of load transmission units, each of which comprises a pair of oppositely positioned angle plates having sockets or housings 55 projecting therefrom. Rigidly secured to each of the housing flanges 13 is a dowel bar which serves to close an opening in the socket or housing. One end of each of the dowel bars is formed to be anchored in a concrete road slab while the 60 opposite end of the dowel bar slidably projects through the filler board and into a chamber of the socket or housing of the opposite angle plate.

The expansion joint forming mechanisms, as illustrated in Figure 1, are adapted to be positioned transversely upon a road sub-grade 1 with the double dowel bars of each of the load transmission units projecting through the opening 5 of the filler board 4 and with the base flanges 7 of the plate 6 resting upon the sub-grade and 70 secured in position by means of retaining stakes 17 which project through openings in the base flanges 7 and are driven into the sub-grade 1 on diagonally opposite sides of the double dowel bars and on opposite sides of the filler board, as clearly 75 illustrated in Figure 1.

With the expansion joint forming mechanism secured in position transversely upon the road sub-grade, concrete is poured on opposite sides of the filler board to form the concrete slabs 2 and 3 and to embed the housings and the anchoring ends 15 of the dowel bars 14. It will thus be noted that the double dowel bars of each of the load transmission units are anchored in the adjacent road slabs and project through an opening 5 of the filler board 4 in slidable overlapping 10 relationship with respect to one another permitting the ends of the dowel bars to project in opposite directions and slidably engage in the chambers 16 of the sockets or housings forming parts of the two angle plates 6 which are positioned 15 on opposite sides of the filler board. With the expansion and contraction of the road slabs due to temperature changes, the overlapping dowel bars of the load transmission units are slidably moved in opposite directions through the filler 20 board and the plates 6. The improved expansion joint also is adapted to transmit loads applied to one of the road slabs through the joint mechanisms to the opposite road slab. The transmission of loads is accomplished by means of the 25 double dowel bar constructions forming part of the spaced load transmission units associated with the filler board 4.

Figures 4 and 5 illustrate a modified form of the load transmission units associated with the apertured filler board. The modified form of load transmission unit comprises spaced angle plates 18 having openings therein with the openings of the opposite plates positioned directly opposite one another. Rigidly secured on the outer face of 30 each of the angle plates 18 is a socket or housing 19 closed at the top, bottom, and at both sides. Upwardly and downwardly projecting flanges 20 are integrally formed on one end of the housing 19 and are spot welded or otherwise rigidly secured to the outer face of the angle plate 18. Integrally formed on the outer end of each of the housings 19 is an end plate 21 which closes only half of the outer end of the housing. Integrally formed with the end plate 21 is a flange 22 which is spot welded or otherwise rigidly secured to a load transmitting dowel bar 23. The double dowel bars shown in Figure 4 are constructed the same as those illustrated in Figure 2 and have the ends thereof projecting in opposite 50 directions in overlapping engagement with respect to one another to span the space between the angle plates 18 so that the ends of the dowel bars slidably project into the chambers 24 provided in the housings 19.

It will, of course, be understood that numerous details of construction may be varied through a wide range without departing from the principles of this invention, and it is, therefore, not the purpose to limit the patent granted hereon otherwise than necessitated by the scope of the appended claims.

I claim as my invention:

1. In an expansion joint for embedding between adjacent concrete road slabs, a preformed 65 plastic filler board mounted between the road slabs and having openings therein, load transmission dowel bars arranged in reverse superimposed slidable contact with one another and projecting through the openings in said filler board, and housing means rigidly secured to each of the dowel bars and embedded in the concrete on opposite sides of the filler board for slidably receiving an end of the other dowel bar.

2. An expansion joint forming mechanism in- 75

- cluding in combination, a preformed compressible 5
filler board having openings therein at spaced intervals, a plurality of pairs of load transmission dowel bars projecting through the openings in
the filler board, each pair of said dowel bars being arranged in reverse superimposed slidable contact with one another, apertured angle plates positioned on opposite sides of the filler board, means for securing the apertured angle plates in position, and housings secured to the outer sides of said angle plates with one of said housings secured to each of said dowel bars and slidably receiving one end of another dowel bar.
3. A road expansion joint comprising a preformed filler board having spaced openings therein, apertured metal plates on opposite sides of the filler board adjacent the openings, apertured base flanges on said plates for supporting the plates in position upon a road sub-grade, housings secured to said plates over the openings therein, and superimposed contacting load transmission dowel bars projecting through said plates and through the filler board, each of said dowel bars secured to one of said housings and slidably projecting into an adjacent housing.
4. An expansion joint forming mechanism including in combination a load transmission unit comprising a pair of spaced plates, a housing rigidly secured on the outer face of each of said plates, a dowel bar secured to each of said housings and having the inner end thereof projecting through the space between said plates and into an opposite housing in slidable contact with the adjacent dowel bar, and anchoring means formed on the outer ends of said dowel bars.
5. An expansion joint forming mechanism in-

cluding in combination a load transmission unit comprising a pair of spaced apertured angle plates, a housing secured on each of said angle plates and a dowel bar secured to each of said housings and projecting through the respective angle plate on which the housing to which it is secured is engaged, said dowel bars being reversed with respect to one another and slidably contacting one another to bridge the space between said angle plates.

6. An expansion joint forming mechanism including in combination a load transmitting unit comprising a pair of reversed apertured angle plates, a housing secured to each of said angle plates, a flange on each of said housings, and a load transmission dowel bar projecting through each plate and housing and rigidly secured to the respective housing flange, said dowel bars projecting in opposite directions in slidable contact with one another to span the space between the angle plates.

7. In an expansion joint for embedding between adjacent concrete road slabs, a preformed plastic filler board mounted between the road slabs and having openings therein, housing members on opposite sides of the filler board adjacent the openings therein and embedded in said road slabs, and pairs of reverse superimposed load transmission dowel bars embedded in the concrete slabs and projecting through the openings in the filler board, each of said dowel bars being secured to one of the housings and slidably projecting through the filler board into a housing on the opposite side of the joint.

ROBERT R. ROBERTSON.
